UNITED STATES PATENT OFFICE.

ALBERT LAMBERT, OF WADSWORTH, OHIO.

AUTOMATIC STEAM-INJECTOR.

SPECIFICATION forming part of Letters Patent No. 416,702, dated December 3, 1889.

Application filed September 12, 1888. Serial No. 285,222. (Model.)

To all whom it may concern:

Be it known that I, ALBERT LAMBERT, a citizen of the United States of America, residing at Wadsworth, in the county of Medina and State of Ohio, have invented certain new and useful Improvements in Automatic Steam-Injectors, of which the following is a specification, reference being had therein to the accompanying drawings.

This invention contemplates certain improvements in injectors for supplying boilers with feed-water, having more especially for its object to adapt it for high-pressure as well as low-pressure steam, while in the event of the heating of the suction or water-supply pipe, or the supply-water being hot, the main forcing-jet is re-enforced by an auxiliary or supplementary jet; and to these ends the invention comprises the combinations of parts, including their construction, substantially as hereinafter fully set forth, and particularly pointed out in the claim.

In the accompanying drawings, Figure 1 is a sectional elevation of my injector. Fig. 2 is a detailed sectional view showing a modification of the main and auxiliary forcing-jet pipes and valves.

In the embodiment of my invention I provide a body or shell A, and within this latter are disposed the lifting-tube a, the "combining-tube" b, and the delivery-tube c. The lifting and combining tubes a and b are provided with successively-reduced tapered chambers, the flared end of the chamber b being about the same area as the tapered end of the chamber a and slightly spaced apart therefrom. The delivery-tube c is also provided with a tapered chamber, the reduced or tapered end of which is disposed just opposite and also slightly spaced apart from the tapered or reduced end of tube b. The tubes a c are connected by suitable means (as, for instance, set-screws) to an internal shell B, suitably applied to the outer shell or body A. Midway of the shell B is applied the tube b, as shown. Intermediately of the tubes a and b is a chamber d, and similarly arranged with relation to tubes a and c is also a chamber e, designated the "spilling-chamber." In alignment with the tubes aforesaid is arranged the main forcing-jet tube C, and around the latter is the auxiliary or supplementary jet-tube C',

communicating at the flared ends of their chambers with the suction or water pipe D, which is controlled by a valve f. The main forcing jet-tube C is controlled by a valve g, while the auxiliary or supplementary jet-tube C' is controlled by a valve g', both arranged in the steam-pipe E, the valve g' opening and closing a chamber g², leading to the jet-tube C'.

In the upper part of the body or shell A is the exhaust or overflow chamber F, communication between which and the chamber d, intermediately of the tubes a and b, is had through an opening f' the entrance to which is closed by a valve F'. Communication is also had between the exhaust or overflow chamber F and the chamber e intermediately of the tubes b and c through the opening f² in shell B. In this chamber F, at its rear end, are the overflow-pipes F², controlled by the check-valve F³, while in the shell or body A, also at its rear end, is a valve G, to prevent the entrance thereto of steam from the boiler.

A' is a cylinder or butt, the outer or extreme rear end of which is adapted (being screw-threaded) for attachment to the boiler. This cylinder or butt is applied to, or, rather, forms in part, the rear end of the body or outer shell A. The inner-end portion of this cylinder or butt is contracted diametrically, thus forming an annular chamber, which unites with short tube or nozzle like sections, as clearly seen in Fig. 1, to form the overflow-pipe F², above referred to. The extreme inner end of the butt or cylinder A' is screwed to the body A and the upper section of the overflow-pipe F² and abuts against and is bolted to the rear flanged end of the delivery-tube c.

In starting the injector the valve g' is opened, permitting the entrance of steam through the jet-tube C' to the lifting-tube a. The steam then passes through the opening f', past the valve F', into the exhaust or overflow chamber F, whence it escapes past the valve F³ into the overflow-pipe F². This action or passage of the steam produces a vacuum in the suction or water pipe D, which effects the lifting of the water thereinto and causes it to take the same course through the injector as that traversed by the steam. The main forcing jet-tube g is now opened, which admits steam to the inflowing water, accele-

rating its flow and directing its passage up between the tubes b c , through the opening f^2 , and into the overflow or exhaust chamber F , whence it passes off or is discharged by means of the overflow-pipe F^2 , its valve F^3 automatically lifting by the action or pressure of the water thereagainst. The pressure of the accelerated flow of water will finally become greater than the boiler-pressure, and thus 5 unseat the valve G and seat the valve F^3 , when the whole flow of the water will be directed to and be caused to enter the boiler past the valve G , thereby effecting the supplying of the latter with feed-water. The 10 flow of water having now become thoroughly established, a partial vacuum will be produced in jet-tube b , which will close the check-valve F' , thus wholly cutting off the overflow. Should, however, the flow of water be momentarily interrupted or withdrawn, it will be restored automatically, thus not requiring the continuous or exclusive attention of the attendant, as under ordinary circumstances the lifting of the water in the pipe D is effected by the jet of the main forcing-tube C independently of the jet of the auxiliary forcing-tube C' . The auxiliary forcing-tube C' is especially of advantage when the suction or water pipe becomes overheated, as in that 15 event it is impossible to lift the water by the jet of the tube C alone; also, by thus being enabled to re-enforce the jet of the main tube C it is possible to get up a flow of water, otherwise impossible when a low pressure of steam is on, while when a high pressure of steam is on it is only necessary to cut off the jet from the tube C' , thus greatly enhancing the utility of the invention, being enabled to do double the service of the ordinary injector. 20

25 In the modification disclosed in Fig. 2 the connection of the spindle or stem, together with its valve g' , is effected through the yoke a' and a screw-threaded connection between it and said stem or spindle, while one valve is

dispensed with, the steam being admitted to 45 the chamber g^2 of the jet-tube C' through the ports a^2 a^3 as said valve is moved sufficiently outward to open said ports. The extension b' of the valve g' projects from the face of the latter sufficiently to exclude steam 50 from the jet-tube C , while steam may enter the ports a^2 a^3 , whereby only the jet-tube C' is in action during the lifting of the water. After this it is only necessary to move the valve farther away from its seat until the 55 extension b' has been withdrawn from the chamber of the jet-tube C in order to put the jets of both tubes C C' in operation.

Having thus fully described my invention, what I claim, and desire to secure by Letters 60 Patent, is—

The injector combining the main forcing jet-tube controlled by a valve, the auxiliary forcing jet-tube around the aforesaid jet-tube and controlled by a valve, the steam-ports for 65 said jet-tubes, the lifting-tube, its flared end being opposite the main and auxiliary jet-tubes, the combining-tube whose flared end is spaced away from and is about the same diameter as the opposite smaller end of the 70 lifting-tube, the delivery-tube having its tapered end spaced away from and about the same diameter as the opposite tapered end of the combining-tube, the valved overflow-chamber communicating with the space-chamber 75 between the lifting and combining tube and with the space or chamber between the combining and delivery tubes, and the overflow-pipe in the rear end of the overflow-chamber, said overflow-pipe having a check- 80 valve, substantially as set forth.

In testimony whereof I affix my signature in presence of two witnesses.

ALBERT LAMBERT.
